United States Patent Office.

JOSEPH W. V. RAWLINS AND SAMUEL STEPHENS, OF HOUGHTON,
MICHIGAN.

Letters Patent No. 91,966, dated June 29, 1869.

IMPROVED ORE-CONCENTRATOR.

The Schedule referred to in these Letters Patent and making part of the same.

To all whom it may concern:

Be it known that we, JOSEPH W. V. RAWLINS and SAMUEL STEPHENS, of Houghton, in the county of Houghton, and State of Michigan, have invented a new and improved Slime Ore-Concentrator; and we do hereby declare that the following is a full, clear, and exact description thereof, which will enable others skilled in the art to make and use the same, reference being had to the accompanying drawings, forming part of this specification.

The object of this invention is to provide an improved machine for cleaning ores of copper, gold-bearing sulphurets, silver-ores, or any other kind of mineral.

The invention consists in a peculiar arrangement of apparatus for spreading the slime upon a slowly revolving table, whereon the ore will be deposited while the water flows over it and away, and from which table the said ore is finally scraped off into a receptacle, all as hereinafter more fully specified.

Figure 1 represents a plan view of our improved machine, and

Figure 2 represents a sectional elevation of the same, taken on the line $z z$ of fig 1.

Similar letters of reference indicate corresponding parts.

A represents a trough, through which the ore is carried by water into a receiver, B, mounted upon the top of a conical table, C, having radiating gutters, D E, calculated to distribute the ore as evenly as possible over the principal part of a conical rotating table, F, the said receiver B being perforated near the bottom, to allow the slime to pass out equally in all directions fronting the receiver.

Through these gutters, D and E, the substance flows, being impelled by the water equally upon the table F, where it is deposited in a thin sheet, allowing the water and light matters to flow off into the circular trough G, having side-issues for the escape of the water and said light matters, while the ore which may be carried off the table will be deposited there.

As the table F, whereon the mass of the ore is deposited, moves slowly around, it passes under the brushes or brooms H, suspended by rods, I, from the table C.

These brushes are divided at the centre for breaking the current of the water, giving it a more gentle flow over the table F.

They also serve to stir the ore and permit the water to act with better effect on the light matter.

After the ore passes all the brooms, it meets currents of clear water fed in through the spout K, and distributing-receiver L, flowing down through the gutters D and E, fronting the said receiver L.

This flow is distributed over the table F, in the space between the last broom and a scraper, M, also suspended from the table C, and in front of which a jet of water is discharged from a pipe, N, leading from the receiver L, and having a cock for regulating it.

This scraper and jet are designed to discharge the ore into the trough G, which is provided with suitable dividing-walls, O, for separating the deposite into different grades.

From these divisions in the receptacle G, the ore may be taken, or allowed to flow out through side-passages, as required.

For operating the table F, it is provided with a large toothed rack, P, on the under side, which is operated by a pinion, Q, on the end of a shaft, having a worm-wheel, R, operated from a shaft, T, and worm deriving motion from any competent power.

The said table rests on rollers, U, and is prevented from lateral movement by guide-rollers, V, working against a tubular projection, W, extending downward around the support X of the table C.

Having thus described our invention,

We claim as new, and desire to secure by Letters Patent—

1. The combination of the receiver B, spout A, guttered table C, revolving table F, and receiving-trough G, all arranged substantially as specified.

2. The combination, with the tables C and F, of the brushes H and scraper M, all arranged substantially as specified.

3. The combination, with the receiver B, guttered table C, table F, and scraper M, of the receiver L, spout K, and pipe N, substantially as specified.

4. The arrangement of the revolving table F, fixed table C, support X, projection W, bearing and guiding-rollers, and operating-mechanism, substantially as specified.

JOSEPH W. V. RAWLINS.

Witnesses: SAMUEL STEPHENS.

SETH REES,
J. P. EDWARDS.
